UNITED STATES PATENT OFFICE.

GEORGE W. BLAIR, OF MISHAWAKA, INDIANA, ASSIGNOR TO MISHAWAKA RUBBER AND WOOLEN MANUFACTURING COMPANY, OF MISHAWAKA, INDIANA, A CORPORATION OF INDIANA.

DESIGN FOR A SHOE SOLE.

Application filed September 27, 1926. Serial No. 19,184. Term of patent 14 years.

To all whom it may concern:

Be it known that I, GEORGE W. BLAIR, a citizen of the United States, residing in Mishawaka, county of Saint Joseph, and State of Indiana, have invented a new, original, and ornamental Design for a Shoe Sole, of which the following is a specification, reference being had to the accompanying drawing, forming a part thereof.

Fig. 1 is a bottom view of the shoe sole showing my new design and Fig. 2 is a sectional view thereof taken on the line 2—2 of Fig. 1.

I claim:

The ornamental design for a shoe sole as shown.
